W.A.Pendergraft, Inventor

John C. Knowles.
Attorney

UNITED STATES PATENT OFFICE.

WILLIAM A. PENDERGRAFT, OF CARNEY, OKLAHOMA.

LEG SPLINT.

Application filed January 11, 1923. Serial No. 612,066.

To all whom it may concern:

Be it known that I, WILLIAM A. PENDERGRAFT, a citizen of the United States, residing at Carney, in the county of Lincoln 5 and State of Oklahoma, have invented a new and useful Leg Splint, of which the following is a specification.

This invention relates to surgical apparatus and more particularly to splints for 10 broken or otherwise injured legs.

The object of the invention is to provide a splint of this character constructed so as to maintain a broken leg in a comfortable normal position and to hold it in such position 15 until the bones knit.

Another object is to so construct an apparatus of this character that it may fit legs of different sizes and which is equipped with removable means to support the leg at various 20 inclinations.

Another object is to provide a splint of this character which may be quickly applied in emergency cases.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings:

Figure 1 represents a side elevation of a 35 splint constructed in accordance with this invention;

Fig. 2 is a top plan view thereof;

Fig. 3 is a transverse section taken on the 40 line 3—3 of Fig. 1, and

Fig. 4 is a similar view taken on the line 4—4 of Fig. 1.

In the embodiment illustrated, the splint 1 constituting this invention comprises an elongated substantially U-shaped member 2, the side rails 3 and 4 of which are designed 45 to lie alongside the opposite sides of the user's leg. These side rails 3 and 4 extend parallel for the major portion of their length and at their outer rear ends diverge as shown at 5 and 6 to conform to the shape of the leg. These diverging ends 5 and 6 telescopically engage hollow side rails 7 and 8, the solid rails 3 and 4 and the hollow rails 7 and 8 being preferably ovate in cross 50 sectional contour as shown clearly in Fig. 4

to prevent them from turning relatively to each other. The ends 5 and 6 are adjustably secured in the hollow rails 7 and 8 by set screws 9 which pass through openings in 60 the side rails 7 and 8 at their front ends and enter apertures 10 in the rail ends 5 and 6, a plurality of such apertures being provided and spaced longitudinally so that the length of the rails may be varied to 65 adapt the apparatus to fit legs of different lengths.

The hollow side rails 7 and 8 are connected at their outer ends by curved hinged- 70 ly connected sections 11 and 12 which provide for the rails 7 and 9 being adjusted laterally toward or away from each other to fit legs of different sizes. These hingedly connected sections 11 and 12 form, when united, a substantially semi-circular thigh 75 support as is shown clearly in Figs. 1, 2 and 4, and are preferably padded as shown at 13 to prevent abrasion of the user's leg.

From the above description it will be seen that the side rails, while adjustable longitudinally to fit legs of different lengths, are substantially rigid throughout their lengths when assembled and may be quickly applied in a manner presently to be described.

The side rails 3 and 4 are provided intermediate their ends on their lower edges with cut out portions 14, having shoulders 15 at their opposite ends, said shoulders being designed to limit the sliding movement of the 80 foot rest 20, hereinafter described in detail.

The foot rest 20 is preferably constructed of woven wire as shown clearly in Fig. 1 and is mounted for longitudinal movement between the side rails 3 and 4, being carried by an upstanding inverted U-shaped 95 sliding hanger 21. The free ends of this hanger are bifurcated as shown in Fig. 3 and the furcations 22 and 23 thereof straddle the side bars or rails 3 and 4 and are equipped with ball or roller bearings to 100 permit them to slide freely on the rails in the cut out portions 14 and are limited in their sliding movement by the shoulders 15 on the lower faces of said rails.

This foot support 20 is shaped to conform 105 to the user's foot as is shown clearly in Fig. 1, and the sole portion 24 thereof is equipped with transversely spaced longitudinally extending slots 25 and 26 through which an attaching strip 27 is designed to 110 pass, connecting the foot support with the foot of the user and with a scale 28 shown

clearly in Fig. 2. This scale 28 being connected with the strap 27 is designed for stretching the leg of the patient and the required traction is placed thereon by turning the wing nut 30 to project or retract the rod 29.

Wire cloth swing-like supports 31, 32 and 33 of desired length and depth are designed to be suspended from the side rails at the 10 opposite sides of the apparatus by means of hooks 34 which are soldered or otherwise secured to the supports. These wire cloth supports form a rest for the leg to be supported. Cooperating transversely 15 curved wire cloth holders 35 and 36 are arranged over the leg opposite the supports 33 and 32 and are held in operative position by means of straps 37 which are preferably made in sections, one being carried by one 20 side rail and the other by the opposed rail, said sections being united by buckles as 38.

Absorbing cotton or other suitable packing, not shown, is designed to be arranged between the leg of the user and the top 25 holder or clamp sections 35 and 36 to prevent them from rubbing the leg of the patient.

The foot rest 20 above referred to, is also constructed of wire cloth and is adjustably connected to the hanger 21 by means 10 of a longitudinally extending apertured plate 39 through which and the member 21 passes a set screw 40 to provide for the lateral adjustment of the foot rest relatively 35 to the rails.

A rest or support 41 elongated U-shaped in form is pivotally connected at its free ends with the foot portion or front end of the member, 2. The legs of said member are 40 offset inwardly at their pivoted ends to permit the support to swing between the side rails 3 and 4. These legs are apertured for adjustable connection with depending brackets 42 carried by the side rails 3 and 4. 45 Set screws 43 hold the members 4 engaged with the brackets, and said brackets are

provided with a number of apertures so that the foot portion of the splint may be raised or lowered to suit the comfort of the user, or the will of the surgeon by 50 changing the position of the member 41 relative to said brackets.

From the above description it will be obvious that the splint constituting this invention may be used on either leg without 55 any change being necessary whatever.

If desired, the supporting stirrup 41 may be folded down flat or removed as may also the brackets 42 with which said stirrups are connected so as to permit the leg to lie 60 out straight. Should the heel of the patient or the ankle be seriously injured, the foot rest 20 may be removed and suitable bandages substituted.

Various changes in the form, shape, proportion and other minor details of construction may be made without departing from the principle or sacrificing any of the advantages of the claimed invention.

I claim:—

A leg splint comprising an elongated substantially U-shaped one piece member, the legs of which are designed to lie along side the opposite sides of the user's legs, said legs being parallel for a portion of their length 75 and then diverging toward their free ends and extended to a point above the knee of the wearer, tubular extensions telescoping with the free ends of said legs and adjustably connected therewith to form side rails 80 which rails are substantially rigid throughout their length, wire cloth leg suspending means for the legs, carried by said side rails, cooperating clamping means connected with said suspending means, and a foot rest 85 adjustably connected with said side rails and means for positioning said rails at varying inclinations.

In testimony that I claim the foregoing as my own, I have hereto affixed my signature.

WILLIAM A. PENDERGRAFT.
